UNITED STATES PATENT OFFICE.

JOHN W. DANIEL, OF COOPERSTOWN, NORTH DAKOTA.

REPAIR RING OR LINK.

1,262,179.

Specification of Letters Patent. Patented Apr. 9, 1918.

Application filed August 18, 1917. Serial No. 186,951.

To all whom it may concern:

Be it known that I, JOHN W. DANIEL, a citizen of the United States, residing at Cooperstown, in the county of Griggs and 5 State of North Dakota, have invented new and useful Improvements in Repair Rings or Links, of which the following is a specification.

This invention relates to improvements in 10 repair rings or links, the primary object of the invention being to provide a handy repair ring or link, which may be readily and conveniently employed for mending or connecting parts of draft appliances, such as 15 halters or harnesses, to effect a connection or enable repairs to be made without the necessity of stitching parts together.

A further object of the invention is to 10 provide a device of the character described which is simple of construction, capable of being made and sold at a comparatively low cost, and which may be employed by anyone 15 of ordinary mechanical skill without the use of special tools.

5 The invention consists of the features of construction, combination and arrangement of parts hereinafter fully described and claimed, reference being had to the accompanying drawing, in which:—

0 Figure 1 is a perspective view of a repair ring constructed in accordance with my invention, showing the ends of the ring prior to connection.

Fig. 2 is a view showing the ring closed 5 and the ends thereof connected.

Fig. 3 is a vertical transverse section 10 through the lapping ends of the ring.

Fig. 4 is a longitudinal section thereof.

The repair device 1 is shown in the present instance in ring form, although it is to be understood that it may be of link form, that is, either round, elliptical or oval, and in practice this ring or link is made of 5 spring wire of any suitable gage and may be made in different sizes to suit various demands of the trade.

The device, properly speaking, as in the form of a split ring or link, and the end portions 2 and 3 of this ring or link are 0 arranged for lapping engagement and are halved to form, when lapped, a scarf or lapped joint. The ends when connected are adapted to be held connected against longitudinal and lateral displacement by interengaging connections and spring action, and 5 also by the use of a transverse screw, rivet

or other suitable fastening 4 engaging registering openings 5 therein. A screw may be conveniently used, in order to avoid the necessity of employing special tools, in which 60 event the openings will be threaded, but a rivet may also be employed with convenience, and may be of a type to be upset or hammered down by the use of a hammer or like simple tool.

Normally the ends of the ring are offset 65 at an angle to each other, giving the ring a substantially spiral formation as a whole, the spring metal of the ring tending to hold the ends spaced or spread both longitudinally as well as laterally. The relatively outer surfaces of the lapping portions 2 and 3 of the ring are provided with interlocking 70 teeth 6, adapted when interlocked, to bring the ends of the ring together, and to cooperate with the transverse fastening 4 to prevent separation of the lapped ends of the ring in a longitudinal direction, a dual form of security against longitudinal separation 75 being thereby secured in a simple and effective manner.

The toothed outer surfaces of the ends of the ring are adapted to be brought into engagement by moving said ring ends laterally in such a manner as to cause them 80 to pass one another in a transverse direction, which may be effected by springing one of the ring ends under the other, until their relative positions are reversed, whereby the normally outer toothed surfaces of 85 the ring are brought to lie on the relatively inner surfaces of the ends of the ring, so that when the ring ends are lapped the toothed surfaces will interengage or interlock, as will be readily understood. When 90 so moved to reversed positions, the tendency of the ring ends will be, by their spring action, to return to their normal positions, so that by such spring action the toothed surfaces of the ring will be held in locking 95 engagement against any tendency to lateral disconnection. Hence by this construction 100 and spring action double security will also be obtained, in conjunction with the transverse fastening 4, to hold the ring ends 105 against spreading and becoming separated in a transverse direction, and the spring action referred to also relieves the fastening screw or member of a large proportion of the holding strain, making a firm and se- 110 cure joint.

It will also be seen that the construction

described also facilitates the application of the fastening member 4, whether in the form of a screw or rivet, since, as the ends of the ring are held connected by their 5 spring action, the screw or rivet may be readily and conveniently inserted without the necessity of the operator holding the ring ends in proper relation or position at the same time.

10. It will thus be seen that my invention provides a device of the character and for the purpose described which is simple of construction, capable of being manufactured and sold at a comparatively low cost, 15 and which affords manifold conveniences in connecting harnesses and other parts for coupling or repair work. It will, of course, be understood that the device may be applied by passing one of the ends of the ring 20 through openings in the parts to be connected and then uniting the ends of the ring to join the parts in the manner described.

Having thus described my invention, I 25 claim:

1. A device of the character described comprising a ring or link made of a continuous length of spring wire, and having lapping end portions normally held by 30 spring action spread in a lateral direction, said lapping end portions being provided

with lateral interlocking surfaces, and means for holding said end portions interlocked against lateral separation.

2. A device of the character described 35 comprising a split ring or link made of spring wire, said ring or link having its end portions spread laterally in spiral relation and provided with relatively outer toothed surfaces adapted for interlocking engagement, said surfaces adapted to be engaged by reversing the position of the ends of the ring, and supplemental means for holding the ends of the ring connected. 40

3. A device of the character described 45 comprising a split ring or link made of spring wire and having end portions arranged to overlap and normally separated on spiral lines, said end portions being provided on their normally outer surfaces with 50 intermeshing teeth and being provided with transverse openings, said end portions of the ring being adapted to be laterally transposed in position for engagement of said toothed surfaces and having openings extending therethrough, and a fastening device adapted to be passed through said openings to supplement the holding action of the toothed surfaces. 55

In testimony whereof I affix my signature. 60

JOHN W. DANIEL.
